(57) **CLAIM**

The ornamental design for a hair brush, as shown and described.

DESCRIPTION

FIG. 1 is a perspective view of a first embodiment of a hair brush, showing my new design.

FIG. 2 is a front view thereof. The back view is the same as the front view.

FIG. 3 is a right side view thereof. The left side view is the same as the right side view.

FIG. 4 is a top view thereof.

FIG. 5 is a bottom view thereof.

FIG. 6 is a perspective view of a second embodiment of a hair brush.

FIG. 7 is a front view thereof. The back view is the same as the front view.

FIG. 8 is a right side view thereof. The left side view is the same as the right side view.

FIG. 9 is a top view thereof.

FIG. 10 is a bottom view thereof.

FIG. 11 is a perspective view of a third embodiment of a hair brush.

FIG. 12 is a front view thereof. The back view is the same as the front view.

FIG. 13 is a right side view thereof. The left side view is the same as the right side view.

FIG. 14 is a top view thereof.

FIG. 15 is a bottom view thereof.

FIG. 16 is a perspective view of a fourth embodiment of a hair brush.

FIG. 17 is a front view thereof. The back view is the same as the front view.

FIG. 18 is a right side view thereof. The left side view is the same as the right side view.

FIG. 19 is a top view thereof; and,

FIG. 20 is a bottom view thereof.
